US00D951236S

(12) **United States Design Patent** (10) **Patent No.:** **US D951,236 S**
(45) **Date of Patent:** **** May 10, 2022**

(54) **EARBUD**

(71) Applicant: **Amazon Technologies, Inc.**, Seattle, WA (US)

(72) Inventors: **Emmanuel Laffon de Mazieres**, San Jose, CA (US); **Marc Rene Walliser**, San Francisco, CA (US)

(73) Assignee: **Amazon Technologies, Inc.**, Seattle, WA (US)

(**) Term: **15 Years**

(21) Appl. No.: **29/818,422**

(22) Filed: **Dec. 8, 2021**

Related U.S. Application Data

(62) Division of application No. 29/785,614, filed on May 26, 2021, now Pat. No. Des. 941,278, which is a division of application No. 29/747,826, filed on Aug. 25, 2020, now Pat. No. Des. 925,497, which is a division of application No. 29/671,625, filed on Nov. 28, 2018, now Pat. No. Des. 900,064.

(57) **CLAIM**

The ornamental design for an earbud, as shown and described.

DESCRIPTION

FIG. 1 is a top perspective view of an earbud. The design includes a mirror image of the embodiment depicted;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the earbud that form no part of the claimed design. The dot-dashed broken lines represent boundaries of the claimed earbud and form no part of the claimed design.

1 Claim, 7 Drawing Sheets
